UNITED STATES PATENT OFFICE.

LEONARD MARION HODGE, OF SAN JOSE, CALIFORNIA, ASSIGNOR OF
ONE-HALF TO WILLIS P. HOLMES, OF SAN JOSE, CALIFORNIA.

CARPENTER'S FRAMING-SQUARE.

No. 830,322.

Specification of Letters Patent.

Patented Sept. 4, 1906.

Application filed July 13, 1905. Serial No. 269,482.

To all whom it may concern:

Be it known that I, LEONARD MARION HODGE, a citizen of the United States, and a resident of San Jose, in the county of Santa Clara and State of California, have invented 5 a new and Improved Carpenter's Framing-Square, of which the following is a full, clear, and exact description.

This invention relates to carpenters' tools, 10 and especially to the type of tool used by such artisans for laying out bevel-cuts for a saw.

The object of the invention is to produce a tool of this class which is especially useful in 15 the construction and framing of roofs.

A special object of the invention is to provide a square of such construction that all of the bevels may be laid off from the square after one setting operation.

20 The invention consists in the construction and combination of parts to be more fully described hereinafter and definitely stated in the claims.

Reference is to be had to the accompanying 25 drawings, forming a part of this specification, in which similar reference characters designate similar parts in all the views.

Figure 1 is a plan of the tool, showing the same applied to two short sections of timber.

30 Fig. 2 is a cross-section taken on the line 2 2 of Fig. 1, upon an enlarged scale. Fig. 3 is an enlarged plan of a portion of the tool, certain parts being broken away, as will appear. Fig. 3^a is a plan of another portion of the tool 35 not shown in Fig. 3, and Fig. 3^b shows the portion of the tool beyond that shown in Fig. 3^a. It will be understood that these last three views taken together will show the complete instrument upon an enlarged scale.

40 Referring more particularly to the parts, and especially to Figs. 1 and 2, A represents the handle stock or body of the square. It is formed of two parallel bars 2, presenting an opening 3 therebetween. At one extremity in the opening 3 a blade C is pivotally attached by means of a bolt 4 and a thumb-nut 5. Near the middle portion of this blade C a blade B is pivotally mounted upon a pin 6, and this blade extends toward the stock A, 45 passing through the opening 3. One of the bars 2 of the body A is provided with a lon-

gitudinally-disposed slot 7, and a corresponding slot 8 is formed in the blade B in the outer portion thereof. Through these slots 7 and 8, which intersect, as indicated, a clamping-bolt 9 passes. This clamping-bolt affords means for rigidly securing the blade B to the handle in any desired position within certain limits. Near the inner extremity of the blade C a longitudinal slot 10 is formed, in which a 55 blade D is adjustably secured by means of a tongue 11^a and a clamping-bolt 11. This blade D projects at right angles to the blade C, as indicated. The outer extremity of the blade C is cut in such a manner as to form a 60 projecting shoulder 12, and the outer extremity of the blade B is of increased thickness beyond the line 13, at which point a shoulder 14 is formed corresponding to shoulder 12 and adapted to receive the same, it being understood that if the blade C were rotated down upon the pivot-bolt 4 the extremity of the blade would come to the line 13 in such a manner as to form a joint. The blade B would then dispose itself in the outer 65 portion of the opening 3. These shoulders 12 and 14 operate not only to limit the inward movement of the blade C, but also to insure that in opening the instrument the parts will be moved in the proper direction. 70

Referring now especially to Figs. 3, 3^a, and 3^b, I provide the upper edge 15 of the handle A with graduations 16 and 17, and near the left is a mark 18, having the number "45°" near the same. On the upper edge 19 of the 75 blade B two similar sets of graduations 20 and 21 are arranged. These numbers all represent a given rise for a given run of a rafter. The set of graduations 16 coöperate with the set 20 and the set 17 with the set 21. 80 The sets of graduations 16 and 20 refer to the rises of common jack-rafters for square roofs, while the graduations 17 and 21 refer to octagonal roofs and to the hips and valleys thereof. In using these graduations to determine the angles or bevels of the cuts to be 85 made with the saw on the jacks the blade B would be manipulated so as to bring the corresponding numerals of the corresponding sets together. Thus, if the pitch ratio of the 90 roof were twelve to twelve, the blade B would be manipulated so as to bring the number 95 100

"12" on the graduations 20 into alignment with the number "12" of the set of graduations 16. The edge 19 would then indicate the proper bevel for the side bevel across the back of the jack, as shown at K² in Fig. 1, at which point a short section 22 of a timber is shown applied to the edge 15 of the square body. The blade C at the point K³, as indicated in Fig. 1, then indicates the plumb cut or down-level, the edge 15 of the body being represented as applied to a timber 23. The blade D in connection with the blade C gives the seat-cut for the rafter, which is found in the angle or triangular point K'. In this way 15 when the square has been set for the proper pitch the three bevels of the jack are indicated on the square and may be laid off immediately by properly applying the square to the timber. On the lower edge of the slot 7 graduations 24 are provided, which are used for finding the bevels for the jacks of octagonal roofs, and a corresponding set 25 of graduations are arranged on the lower edge and outer extremity of the blade B. The manipulation of the instrument would be the same as before in finding the bevels for octagonal jacks, it being understood that the corresponding numbers representing the pitch ratio of the roof would be brought into 25 alignment. Similar sets of graduations are placed on the stock A and blade B, which will give the bevels for common or octagonal hips and valleys, also for common or octagonal raking plancher edge cuts. Also the 30 bevels for common or octagonal hip backing may be found in the same manner.

At suitable points on the handle A tables 26, 27, and 28 are placed, which will give the lengths of rafters for different roof pitches.

40 The edge of the blade C, which is remote from the direction in which the blade B extends, is formed into a scale indicating inches, as shown. The edges of the blade D are likewise formed into scales.

45 It will be observed that by loosening the clamping-screw 11 the blade D can be shifted on the blade C toward or from the body A of the square. In this way any desired rise from the edge of the blade D to the back of 50 the rafters can be produced in laying off the seat-bevel. The raking plancher-cuts also give the angles for both face and edge cuts for facies, sheathing, shingles, &c., at the hips and valleys of both square and octagonal roofs. The blades C and D enable mortises 55 or tenons to be cut in an inclined position upon a timber. The blade C being held rigidly upon the body A would be shifted into a position parallel with the former position in order 60 to lay off two of the sides of the tenon, and the blade D could be shifted upon the blade C so as to give the other two sides of the tenon. In a similar manner housings and stringers for

stairs could be laid out at any desired pitch. If it were desired to use the square for making mortises or tenons the sides of which are parallel with the sides of the timber, the blade B would then be adjusted until the graduation on its edge marked "45°" comes to the "45°" mark 18 referred to above. 65 When clamped in this position, it would hold the blade C at right angles to the body A, and the plate D would then be parallel with the body A and with the sides of the timber resting against the body A. In this way the 70 edges of the blades C and D would afford means for drawing lines parallel with the axis of the timber or transverse thereto, and the instrument would then constitute a square and a bevel-square. 75

80 When the instrument is to be used as a square, the blade D may be detached from the blade C, in this way leaving the graduated edge of the blade C entirely free from obstructions. Furthermore, the blade B may be adjusted at its free end, so that its extremity would not project beyond the lower edge of the body A, as indicated in Fig. 1. In this way the square could be adapted for application to a corner made between two walls as 85 though it were a common square, or, if desired, both blades B and D may be entirely detached, leaving only the blade C, and the instrument may then be used as an ordinary bevel or square. 90

95 While I prefer to use the form of body A which has been described, this form is not essential, and it should be understood that the essential feature of the instrument in this particular is the running and free connection 100 between the blade B and the body A.

Having thus described my invention, I claim as new and desire to secure by Letters Patent—

1. In an instrument of the class described 105 having a body, a blade pivoted thereto, a second blade pivoted to said first blade and adjustably connected with said body, and a third blade carried by said first blade and projecting away from said second blade in a direction substantially at right angles to said first blade.

2. In an instrument of the class described, 110 having a body, a blade pivoted thereto, a second blade pivoted to the first blade and adjustably connected with said body, and a third blade projecting away from the said second blade attached to said first blade at right angles thereto and having unobstructed marking edges on each side thereof. 115

120 3. An instrument of the class described, having a body, a blade having a pivotal connection therewith, a second blade having a pivotal connection with said first blade, means for adjustably connecting said second blade to said body, said second blade and

said body having coöperating graduations, a third blade attached substantially at right angles to said first blade between said pivotal connections and projecting away from said 5 second blade, and means for guiding said third blade longitudinally upon said first blade.

In testimony whereof I have signed my name to this specification in the presence of two subscribing witnesses.

LEONARD MARION HODGE.
